UNITED STATES PATENT OFFICE.

CLAUDE E. PARKER, OF MOUNTAIN VIEW, CALIFORNIA, ASSIGNOR TO PARKER PENCIL COMPANY, INC., OF LOS ANGELES, CALIFORNIA, A CORPORATION OF CALIFORNIA.

VENDING MACHINE.

Application filed April 16, 1925. Serial No. 23,621.

The present invention relates to improvements in check controlled apparatus of the article delivery type, and has particular reference to a machine adapted for delivering 5 a lead pencil upon the depositing of a coin within the machine.

The general object of the invention is to provide for maintaining a stack of lead pencils or like objects within a compartment 10 or magazine of a vending machine so that the components of the stack will move automatically and successively, one at a time, to the delivery apparatus without liability of derangement or jamming which would render 15 the machine inoperative.

The above and other objects are accomplished by instrumentalities pointed out in the following specification.

The invention is clearly defined in the 20 claims.

A satisfactory embodiment of the invention is illustrated in the accompanying drawings forming part of the specification and in which—

25 Figure 1 is a front elevation of the complete machine, a part of the front wall being broken away to disclose the construction and relation of other parts.

Figure 2 is a vertical cross-section on the 30 line 2—2 of Figure 1.

Figure 3 is a vertical cross-section on the line 3—3 of Figure 1.

Figure 4 is a detail side elevation of the 35 check controlled apparatus in locked position, and

Figure 5 is a view of the parts shown in Figure 4 and looking at right angles thereto.

The cabinet *a* of this machine is herein shown as formed of metal and when in use 40 may be arranged upright upon a counter or other support or, if desired, the machine may be suspended from a vertical support. The bottom or base plate 5 of the machine is flat and secured to the lower end portions 45 of the vertical side walls 6—6 and the front wall 7. The upper portion of the front wall 7 is extended laterally as indicated at 8 and this lateral extension forms the top of the cabinet, the free edge extending to a point

50 in vertical alinement with the free edge of the base plate 5 where a rabbet 9 is formed to receive an edge of a panel 10 constituting the back of the machine, the lower end of the panel having a rabbet 11 to receive

the upturned end portion 12 of the base 55 plate 5. A suitable key operated lock 12 is provided for locking the back in the position shown in Figure 3, a bolt 13 of the lock engaging behind a lug 14 depending from the top 8. At suitable spaced intervals the 60 opposite side portions of the front wall 7 are provided with perforated lugs 15 through which screws 16 extend, the screws being screwed into the side plates 6—6 thereby operating to connect the side and 65 front walls together; the base plate 5 being also secured to the side walls by the screws 17. A transverse article delivery opening 18 is provided in the lower portion of the front wall 7 and extending upwardly and inwardly from the opening 18 is a slide 19, the lower outer end of which is disposed below the upper side of a recess on the lower side of opening 18 so that the projecting portion 20 of the lower side of the opening 70 operates as a stop that prevents an object moving down the slide from falling outwardly through the opening 18. In Figure 75 1 a recess 21 is formed through the upstanding portion 20 and affords access with the fingers to an object held by the stop so that the object may be readily lifted through the delivery opening 18. The upper end of the slide 19 supports an inclined tray 22 which extends transversely of the interior of the cabinet and operates to divide the interior 80 into an upper compartment or magazine 23 and into a lower or delivery compartment 24. The compartments 23 and 24 are in communication through a space 25 which results from the front lateral edge of the tray terminating in spaced relation to the front wall 7. The front wall 7 is curved inwardly 85 at the portion thereof opposite the outer edge of the tray so as to reduce the side of 90 the passage 25 to approximate the diameter of an ordinary lead pencil or other like object to be vended in connection with this machine.

It will be noted by reference to Figure 3 100 that the space 25 is less than the combined diameters of two pencils and somewhat greater than the diameter of one pencil, so that ample room will be afforded for the passing of a pencil through the passage. A 105 carrier comprising a pair of arms 26 is disposed below the passage 25 and the arms have detents, one of which is shown at 27

in Figure 3. These detents are adapted to receive a single lead pencil and support the same horizontally as shown in Figures 1 and 3. The carrier is turnable and the arms thereof are secured to a rock shaft 28 which is journaled in the end walls 6-6 and extended at one end beyond one of the end walls at which portion it is provided with an operating handle 29. The arms 26 are so proportioned that the detents thereof form continuations of the passage 25 and lateral curved extensions 30 of the arms are so proportioned and disposed as to form closures for the passage 25 by extending from across when the shaft 28 is turned and the detents moved away from the passage 25. A vertical partition 31 disposed within the cabinet a cooperates with the end wall on the left of Figure 1 to reduce the transverse length of the magazine 23 and compartment 24 to conform approximately to the length of a new lead pencil. This partition 31 has an opening for the reception of shaft 28 and is secured by fastening devices passing through lugs 32 to the front wall of the cabinet. A flange 33 extends laterally from the rear edge portion of the partition 31 and functions as a keeper to prevent outward displacement of the lead pencils when the back or panel 10 is removed. In this connection a vertical rod 34 arranged in spaced relation to the flange 33 and connected to the tray 19 by bearing on another portion of the lead pencils within the magazine cooperates with the flange to prevent displacement of the pencils when the back 10 is removed. As shown in Figures 1 and 3, the magazine is adapted for containing a stack of lead pencils 35 which are insertable into the magazine by directing their respective ends between the flange 33 and vertical rod 34. It will be noted that the capacity of the magazine is such that a considerable number of pencils may be arranged therein and in practise a sufficient number of pencils to fill the magazine are usually arranged therein when the machine is placed in use.

Obviously the pressure from the pencils of the stack upon those pencils adjacent to the passage 25 is relatively great and, while the length of the magazine is such that end-wise movement, which would result in skewing, is avoided as near as possible, nevertheless the pressure of the entire stack might, under certain conditions, such as irregularity in the dimensions of some of the lead pencils, cause the same to bind in the passage 25. In order to overcome such liability, the arms 26 are provided with outwardly extending fingers 36 which are movable into and out of slots in the tray 22 when the shaft and arms are turned.

Referring to Figure 3, it will be noted that the upper end portion of the finger 36 extends for an appreciable distance into the

magazine and into the path of movement of the lower tier of pencils 35 which tier it intercepts and by so doing removes the lateral pressure transmitted to this tier of pencils upon the pencil disposed immediately above the passage 25. In addition when the finger 36 is moved out of the recess in the tray 22, a space is left into which the lower-most pencils of the stack may move. This may result in a movement of all the pencils of the stack and is the equivalent of agitating the pencils in order to prevent their binding one upon the other. Upon return movement of the fingers into the magazine, the stack is again agitated. Thus adequate means are provided in each operation of the machine to prevent binding of the contents thereof.

Referring now to Figures 1 and 3, a substantially U-shaped stay 37, herein shown as formed of a single length of wire, is secured to the front wall 7 by screws 38 extending through eyes 39 in the terminals of the sides of the stay and screwed into bosses, one of which is shown and indicated by 40 in Figure 3, which are carried by the upper end portion of the front wall 7. The body of the stay is directed downwardly and inwardly so that the lower horizontal portion 41 is disposed in spaced relation to a transparent panel 42 of glass or the like disposed in the cut-out portion of the front wall and forming a side wall of the magazine 23 and through which the contents of the magazine is displayed. The intermediate portion of the sides of the stay are directed outwardly, as indicated at 43, so as to bear on the plate 42. In this manner that portion of the stay downwardly and beyond the portion 43 is rendered resilient. The spacing between the horizontal portion 21 of the stay and the plate 42 conforms substantially to the width of the passage 35 and the horizontal portion 41 is disposed somewhat above the said passage. In this position the lateral and to a great extent the vertical pressures exerted by the upper portion of the stack when the magazine is filled with pencils is directed upon the stay 37 and enables this element to cooperate with the finger 36 in relieving the several pencils disposed in vertical alinement with the passage 35 of the relatively great pressure of the stack. This construction, moreover, adds to the attractiveness of the machine as a whole in that, when viewed from the front through the panel 42, those of the pencils which are visible appear in an outwardly inclined row superimposed upon a vertical row.

The machine of this invention is designed to operate upon the depositing of a coin therein and for this purpose is provided with a coin slot 44 in one of the upper corners of the front wall 7, which slot communicates

with a chute 45, the passage of which is contracted at its lower end to a diameter less than the coin indicated by 46 in Figure 4. At 5 the lower end the front and rear side walls of the passage are cut away so that when the coin is positioned as shown in Figure 4, the segment on the right in that figure projects beyond the adjacent side of the chute. A tumbler 47 is pivoted to a side wall of 10 the cabinet *a* and extends downwardly and transversely of the chute and terminates in a lateral extension 49 which forms a closure for the rear open side of the lower end portion of the chute. A retractile spring 50 15 connected at one end to the extension 49 and at its opposite end to a lug 51 carried by the adjacent side wall, operates to yieldingly hold the extension 49 of the tumbler 47 over the open side of the recess of the chute 45. 20 A collar 52 secured to shaft 28 is provided with a segmental lug 53 which normally extends vertically upward as shown in Figure 2. The movement of shaft 28 in a clockwise direction with respect to Figure 2, is 25 limited by a lug 54 forming part of another extension 55 of the collar 52 which lug 55 abuts the lug 51. A retractile spring 56 secured at one end by a screw 57 to the side of the chute 45 extends downwardly and is connected to a radially extending pin 58 carried by shaft 28. A forwardly projecting finger 59 and tumbler 47 extend into the 30 path of movement of the segmental lug 53 when shaft 28 is turned by the handle 29 so that when the lug 53 abuts finger 59, the pressure exerted by the lug is vertically downward so that the tumbler 47 will not move. This action will take place whenever 35 the handle is turned and when the presence of a coin of required size is not present in the lower end of the chute.

* Referring now to Figures 2 and 4, the extension 55 is provided with a segmental portion 60 projecting beyond the face of the extension or lug 53. This extension 60 is in alinement with the inner open side of the chute so that when a coin moves to the lower end of that member, the turning of shaft 28 will move extension 60 into contact with the coin and continued movement of the shaft will operate to move the tumbler through the coin and lift finger 59 out of the path of movement of the extension 53. The tumbler 47 will move, under the action of the coin, until sufficient clearance exists between the chute and the extension 49 to permit the coin to drop from engagement between the extension 60 and the extension 49. During this turning movement of the 50 shaft, the arms 30 are turned to the left in

Figure 3, and the lowermost pencil is conveyed through an arc of more than 90° whereupon the pencil falls upon the slide 19 and is delivered to the opening 18. Upon releasing the handle, the springs 50 and 56 65 operate to restore the parts to their normal positions as shown in Figure 2.

Although I have shown and described one embodiment of my invention, it is to be understood that the same is susceptible of various changes; and I reserve the right to employ such as may come within the scope of the appended claims.

I claim:

1. A pencil vending machine having a 75 magazine formed with an inclined bottom having an outlet, a delivery mechanism regulating the outlet and means for continuously grouping a series of pencils in vertical alinement with the delivery mechanism and for holding the other pencils with respect thereto so as to provide a relatively constant uninterrupted source of supply for which pencils will be fed automatically into the delivery mechanism, said grouping means 80 comprising a substantially U-shaped stay formed of a single length of wire secured to the front wall of the magazine and including a body portion directed downwardly and inwardly so that the lower horizontal 85 portion of the stay is disposed in spaced relation to said front wall and at a point above and in spaced relation to the intake end of the delivery mechanism, so that a part of the merchandise is at one side of the stay 90 and a part at the other side thereof.

2. A pencil vending machine having a 100 magazine formed with an inclined bottom having an outlet, a delivery mechanism regulating the outlet and means for continuously grouping a series of pencils in vertical alinement with the delivery mechanism and for holding the other pencils with respect thereto so as to provide a relatively constant uninterrupted source of supply for which 105 pencils will be fed automatically into the delivery mechanism, said grouping means comprising a substantially U-shaped resilient stay formed of a single length of wire secured to the front wall of the magazine and including a body portion directed downwardly and inwardly so that the lower horizontal portion of the stay is disposed in 110 spaced relation to said front wall and at a point above and in spaced relation to the intake end of the delivery mechanism, so that a part of the merchandise is at one side of the stay and a part at the other side thereof.

CLAUDE E. PARKER.
